(No Model.)

I. ROBINSON.
POST HOLE AUGER.

No. 309,803.

Patented Dec. 23, 1884.

UNITED STATES PATENT OFFICE.

ISIAH ROBINSON, OF SPRINGTOWN, ASSIGNOR TO HIMSELF, AND J. W. SUBLETT, OF MANSFIELD, TEXAS.

POST-HOLE AUGER.

SPECIFICATION forming part of Letters Patent No. 309,803, dated December 23, 1884.

Application filed April 16, 1884. (No model.)

To all whom it may concern:

Be it known that I, ISIAH ROBINSON, of Springtown, in the county of Parker and State of Texas, have invented a new and Improved 5 Post-Hole Auger, of which the following is a full, clear, and exact description.

The object of my invention is to provide a new and improved machine for boring holes for fence-posts, &c.

10 The invention consists of the sundry combinations of parts, substantially as hereinafter fully set forth and claimed.

Reference is to be had to the accompanying drawings, forming part of this specification, 15 in which similar letters of reference indicate corresponding parts in all the figures.

Figure 1 is a longitudinal sectional elevation of my improved post-hole auger on the line $x-x$, Fig. 2. Fig. 2 is a cross-sectional elevation of the same on the line $y-y$, Fig. 1. 20 Fig. 3 is a sectional view of the lower end of one of the legs of the frame, showing the means for varying the height of the legs. Fig. 4 is a detail face view of one of the cog-wheels for 25 raising the frame. Fig. 5 is a face view of the ratchet-wheel for engaging with the above-mentioned cog-wheel. Fig. 6 is a detail vertical section through one set of the half-nuts, 30 including side views of their adjusting-screw and one of the platform-adjusting screws partly broken off.

A shaft, A, is journaled in two uprights, A', on the top of the frame B of the machine, and on the said shaft is mounted a bevel cog-wheel, 35 C, engaging with a bevel-pinion, D, mounted rigidly on the upper end of a squared shaft, D', which is held between uprights E, united at the lower ends by a cross-piece, E', which bars E form the holder for the auger-bit, and 40 are adapted to slide vertically on the squared shaft D', being held at their point of adjustment, it may be, by an adjusting-screw, or a pin passing through coincident holes in said bars E and shaft D'. The two bars E pass 45 through a horizontal cog-wheel, F, mounted to revolve on a horizontal platform, G, held between the parallel vertical bars G', secured to cross-bars at the ends of the frame B.

Between the bars E a U-shaped piece or clip,

H, is secured to the under side of the wheel 50 F, and is adapted to receive the upper end of the stock in which the auger-bit is held. A bolt, H', is then passed through an aperture in the stock and through the clip H. The stock is also passed through an aperture in 55 the cross-bar E' uniting the bars, E. Two cog-wheels, K, engaging with the cog-wheel F at diagonally-opposite points, are rigidly mounted on the ends of screw-spindles L, held to turn in the platform G, and projecting upward, 60 the upper parts of the said screw-spindles passing through an intermediate platform or partition, A², of the frame, and through the top of the frame. Two rack-bars, N, are hinged to jaws N', projecting upward from the platform G, and pass through apertures in the horizontal platform A², and through the top of the frame. The smooth edges of the said rack-bars run on rollers N'', held in the upper horizontal forked ends of the standards N' on the 70 horizontal platform or partition A². Each rack N engages with a cog-wheel, O, mounted loosely on a shaft, P, journaled in uprights P' on the horizontal partition or platform A², between which uprights the cog-wheels O are 75 held, which shafts are provided with two opposite longitudinal grooves, L'.

On the inner end of each shaft P a beveled cog-wheel, Q, is mounted, to engage with a bevel cog-wheel, Q', pivoted to revolve in a 80 horizontal plane on the intermediate platform or partition, A², through which cog-wheel the bars E pass, so that the said cog-wheel will revolve with the said bars. Each cog-wheel O is provided in its outer flat surface with two 85 ratchet-teeth, o, (see Fig. 4,) adapted to engage with corresponding ratchet-teeth, r, (see Fig. 5,) on the juxtaposed end of a sleeve, R, adapted to receive the shaft P, and adapted to be pressed against the side surface of the corresponding wheel O. The sleeve R is provided on its inner surface with two longitudinal ridges or ribs, s, (see Fig. 5,) adapted to pass into the grooves L' of the shaft P. The outer end of each sleeve R is flanged, and is 90 held to revolve in a block, S, provided with a threaded aperture, and forming one-half of a 95 nut for the corresponding spindle L. The

blocks S and S' form the said nuts, and the block S' is rigidly mounted, whereas the block S is movable. A screw, T, having a right and left thread, works in the blocks or half-nuts 5 S S', said threads bearing, respectively, in said nuts, whereby upon turning said screw the block S can be moved toward or from the block S', and as the sleeve R is held upon said block S' the sleeve R will move with the block S toward or from the corresponding wheel O. Two hook-latches, V, are pivoted to the sides of the frame and hang downward, and springs 10 V' press the upper ends outward, thereby pressing the lower ends inward, so that if the platform G is moved upward it automatically 15 catches on the said latches and is locked in position. Each leg B is provided with a longitudinal aperture in its lower end, and in the said aperture a toothed bar, W, is held, 20 on the lower end of which a triangular or other foot, W', is formed. A latch, U, is pivoted to the side of the stock, and is provided with a prong adapted to engage with the teeth of the rack W, and thus lock the rack in position. 25 The rack W can be released from the catch U, and can be projected a greater or less distance from the lower end of the leg, thus permitting of leveling the machine and holding it any suitable distance above the ground.

30 The operation is as follows: The bit-stock is passed through the apertured cross-bar E', uniting the bars E, and the upper end of the stock-bar is held in the U-shaped clip H. If the shaft A is revolved, the bevel cog-wheel C and the pinion D are also revolved, and revolve the squared shaft D' and the bars E, which in turn revolve the cog-wheel F and the stock, causing the bit or scoop to form a hole in the ground; but it is necessary to press the frame G 35 downward continually, as the wheel F, in which the upper end of the stock is held, is mounted on the said frame or platform. This is accomplished by means of the screw-spindles L, which are revolved from the cog-wheel F by 40 the cog-wheels K. The nut-sections S and S' are clamped together, so that if the screw-spindles L are revolved from the bars E they will revolve in such a manner as to move the platform G downward gradually, and at a rate 45 of speed proportionate to the speed of the auger bit or scoop. If it is desired to raise the platform G and withdraw the auger from the hole, the screw T is turned in such a manner as to separate the blocks S and S', whereby 50 the nut-blocks S will be moved toward the outer surfaces of the wheels O, and the teeth r on the outer ends of the sleeves R will engage with the teeth o on the wheels O, and at the same time the longitudinal ridges s, formed 55 on the inner surfaces of the sleeves R, will pass into the grooves L' of the shafts P, thus engaging the said sleeves R with the shafts P, which are revolved by the beveled cog-wheels Q, and revolving the sleeves R, which, being 60 engaged with the cog-wheels O, revolve the same, and the said cog-wheels move the racks N upward, thereby raising the platform G.

The shaft A, which drives the entire mechanism, can be revolved by hand, or by means of any suitable motor, as may be desired. 70

Having thus described my invention, what I claim as new, and desire to secure by Letters Patent, is—

1. In a post-hole auger, the combination, with the tool-guiding uprights and their revolving gearing, of the tool-carrying pinion, with the tool-securing contrivance fastened to its under side between said guiding-uprights, said pinion being adapted to revolve with said guiding-uprights, and the platform with its 75 lowering screw or screws geared with the tool-carrying pinion, substantially as and for the purpose set forth.

2. In a post-hole auger, the combination, with means for revolving the auger, of a vertically-movable platform or partition on which the auger is held, screw-spindles projecting upward from the said platform, and nuts formed of two sections, through which nuts the spindles pass, and means for revolving the spindles 80 from the means of revolving the auger, substantially as herein shown and described. 85

3. In a post-hole auger, the combination, with means for revolving the auger, of a vertically-movable platform or partition on which the auger is held, spindles projecting upward 90 from the said platform, nuts through which the spindles pass, which nuts are formed of two sections, a screw for separating the sections or bringing them together, and means for revolving the spindles from the means for revolving the auger, substantially as herein shown and described. 95

4. In a post-hole auger, the combination, with means for revolving the auger, of the vertically-movable platform G, the cog-wheel F, pivoted on the platform G, and adapted to hold the upper end of the auger-stock, the cog-wheels K, engaging with the cog-wheel F, the screw-spindles L, projecting upward from the cog-wheels K, and nuts through which the screw-spindles pass, substantially as herein shown and described. 100

5. In a post-hole auger, the combination, with the upright bars E, between which the auger-bit is held and guided, of the vertically-movable platform G, the cog-wheel F, pivoted on the same, through which cog-wheel the bars E pass, the cog-wheels K, engaging with the cog-wheel F, the screw-spindles L, projecting upward from the cog-wheels K, and nuts through which the said spindles pass, substantially as herein shown and described. 115

6. In a post-hole auger, the combination, with the upright bars E, for holding and guiding the auger, of means for revolving the said bars, the beveled cog-wheel Q', through which the bars pass, the beveled cog-wheels Q, mounted on the shafts P and engaging with the beveled cog-wheel Q', the cog-wheels O, mounted loosely on the shafts P, the racks N, engaging with the cog-wheels O, means for revolving the cog-wheels O with the shafts P, the vertically-movable platform or partition 120

G, to which the racks N are secured, and means for moving the platform G downward as the auger revolves, substantially as herein shown and described.

5 7. In a post-hole auger, the combination, with the vertical bars E, for guiding and holding the auger, of means for revolving the said bars, the beveled cog-wheel Q', through which the said bars pass, the beveled cog-wheels Q, engaging with the beveled cog-wheel Q' and mounted on the shafts P, provided with longitudinal grooves L', the cog-wheels O, mounted loosely on the shafts P, and provided in their outer surfaces with teeth o, the sleeves R, provided with teeth r, adapted to engage with the teeth o on the cog-wheels O, the movable blocks S, in which the sleeves R are held to revolve, the blocks S', the screws T,

the screw-spindles L, the cog-wheels K on the vertically-movable platform G, and the cog-wheel F, engaging with the cog-wheels K, through which cog-wheels F the bars E pass, substantially as herein shown and described.

8. In a post-hole auger, the combination, with a frame, of the squared shaft D', provided with means for revolving it, the vertical bars E, secured on the shaft D', the apertured cross-piece E' on the lower ends of the bars E, and the clip H, for holding the upper end of the auger-stock, substantially as herein shown and described.

ISIAH ROBINSON.
